(57) **CLAIM**

The ornamental design for a decorative container for a wine bladder, as shown and described.

DESCRIPTION

FIG. 1 is an isometric view of a decorative container for a wine bladder illustrating a top portion, a bottom portion, and a base;

FIG. 2 is a front view thereof;

FIG. 3 is rear view thereof;

FIG. 4 is a left hand side view thereof, wherein a right hand side view is a mirror image of the left hand side view;

FIG. 5 is a top view thereof;

FIG. 6 is a bottom view thereof;

FIG. 7 is an isometric top view of the decorative container for a wine bladder showing the top portion only, the rest removed for ease of illustration;

FIG. 8 is an isometric bottom view thereof;

FIG. 9 is an isometric top view of the decorative container for a wine bladder showing the bottom portion only, the rest removed for ease of illustration;

FIG. 10 is an isometric bottom view thereof;

FIG. 11 is an isometric top view of the decorative container for a wine bladder showing the base portion only, the rest removed for ease of illustration; and,

FIG. 12 is an isometric bottom view thereof.
